UNITED STATES PATENT OFFICE.

WILLIAM HENRY DEAN, OF SIOUX CITY, IOWA.

STREAM-DEFLECTOR.

1,151,445.

Specification of Letters Patent. Patented Aug. 24, 1915.

Application filed June 23, 1914. Serial No. 846,775.

To all whom it may concern:

Be it known that I, WILLIAM HENRY DEAN, a citizen of the United States, and a resident of Sioux City, in the county of 5 Woodbury and State of Iowa, have invented a new and Improved Stream-Deflector, of which the following is a full, clear, and exact description.

The invention relates to stream deflectors 10 for use in rivers and other waterways and such, for instance, as shown and described in the Letters Patent of the United States, No. 1,080,049, granted to me on December 2, 1913.

15 The object of the invention is to provide a new and improved stream deflector arranged to cause the current in the waterway to form a building current and to prevent the current from digging into the shore or 20 bank of the waterway.

In order to accomplish the desired result 25 use is made of two aprons disposed vertically and extending at an acute angle one relatively to the other, the apex of the aprons being in the waterway a distance from the shore thereof and the aprons extending toward the shore, the lower edges of the aprons being spaced from the bottom 30 of the waterway for the current to flow under the upstream apron and rise between the aprons to then flow downward and under the downstream apron.

A practical embodiment of the invention 35 is represented in the accompanying drawings forming a part of this specification, in which similar characters of reference indicate corresponding parts in all the views.

Figure 1 is a perspective view of the 40 stream deflector as applied; Fig. 2 is a cross section of the same; Fig. 3 is a sectional side elevation of the same.

The stream deflector consists essentially 45 of two vertically-disposed aprons A and B extending at an acute angle one relatively to the other, the apex of the aprons being in the waterway C a distance from the shore C¹ thereof and the aprons extending toward the shore. The aprons A and B are inclined at their lower edges to follow the bottom 50 of the waterway, and the said lower edges are provided with openings or serrations A¹, B¹ for the current to flow through the openings A¹ to rise between the aprons A and B and to then flow down adjacent 55 the inner face of the downstream apron B to finally pass through the openings B¹,

the current thus forming a building current for forming a bar by depositing sand or other material below the apron B as indicated in Fig. 3. When the water in the 60 waterway is low the lower edges of the aprons A and B rest on the bed of the waterway C but when the water rises the aprons A and B float and rise a distance which is limited by anchored flexible connections E 65 and E¹, of which the flexible connection E is attached to the apex of the aprons and is connected with an anchor F embedded in the bed of the waterway C. The flexible connections E¹ are connected with the shore 70 ends of the aprons A and B and are attached to anchors F¹ embedded in the bed of the waterway C. In case the water rises very high it can flow over the upper edges of the 75 aprons A and B.

In order to hold the aprons A and B in position against the force of the current, use 80 is made of flexible connections G and G¹ connected with the ends of the aprons A and B and with anchors H and H¹ arranged in the bed of the waterway on the upstream and downstream sides of the deflector, as will be readily understood by reference to Fig. 1. The aprons A and B are connected with each other at the upper edges by 85 spaced beams I and I¹ and braces I² to give the desired rigidity to the aprons. Below the rear beam I is arranged a beam I³ and to the beams I and I³ are secured vertically 90 disposed slats I⁴ to provide a space between the shore ends of the aprons A and B for the reception of brush or similar filling material to prevent the current from cutting the bank at the shore line.

The apex end of the connected aprons A 95 and B is provided with a box or shelf J containing rocks K or other weighting means to hold the stream deflector downward in proper relation relatively to the bed of the waterway C.

In constructing the aprons A and B use 100 is preferably made of vertical planks attached to transverse top and bottom beams, the lower ends of the planks being alternately longer and shorter so as to provide the openings or serrations A¹ and B¹ previously mentioned.

Having thus described my invention, I 110 claim as new and desire to secure by Letters Patent:

1. A stream deflector, comprising connected and vertically disposed aprons ex-

- tending at an angle one to the other and adapted to be set in the waterway transversely to the current with the apex end a distance from the shore, each apron comprising upper and lower beams, the lower beams being inclined, and a plurality of vertical boards secured to the said beams, alternate boards being longer and extending below the lower beam.
- 10 2. A stream deflector, comprising connected and vertically disposed aprons extended one from the other at an acute angle and adapted to be set in the waterway transversely to the current therein with the apex end in the waterway a distance from the shore, the aprons being connected by transverse partition formed of upper and lower beams and vertical spaced slats and forming a space for a filling material, the lower edges of the aprons being spaced from the bed of the waterway for the current to flow under the aprons to form a building current for forming a sand bar a distance down stream beyond the apron.
- 15 25 3. A stream deflector, comprising connected vertically disposed aprons set in the waterway transversely to the current therein

and diverging from a common point in the waterway toward the back thereof, the lower edges of the aprons being for the current to flow through the said apron to form a building current, flexible connections connected with the ends of the said aprons, and anchors in the bed of the waterway and to which the said flexible connections are attached.

4. A stream deflector, comprising connected and vertically disposed aprons arranged at an angle to each other and adapted to be set in the waterway transversely to the current, each apron comprising upper and lower beams and vertical boards secured to the beams with alternate boards extending below the lower beam, and means for anchoring the deflector whereby it can rise and fall with the water of the waterway.

In testimony whereof I have signed my name to this specification in the presence of two subscribing witnesses:

WILLIAM HENRY DEAN.
